PROTECTIVE STORAGE RECEPTACLE

Isadore Kamman, Gardner, Mass., assignor to
Kamman Furniture, Inc., Philadelphia, Pa., a
corporation of New York

Application February 9, 1942, Serial No. 430,115

1 Claim. (Cl. 206—10)

The present invention relates to protective storage receptacles for storing and protecting from moths and the like those articles of apparel and of household use which are subject to damage by such insects.

At the present time there are several ways which are commonly employed for protecting such articles from the ravages of these insects. One method is to wrap the article with camphor, naphthalene, commonly known as moth balls, or other suitable protective material, in cloth or paper wrappers. Often the moth balls are placed in the various pockets of the garments which are then hung in a more or less tight closet. Another common practice is to fold the garments or other articles with moth balls scattered between the folds, placing the folded garments in drawers of storage chests or other receptacles.

While these methods are reasonably effective in protecting the articles, they not only involve time and trouble in preparing the articles for storage and removing them therefrom, but due to the intimate contact of the moth balls or other protective material, the garments become so saturated with the pungent odor of such material that they are unfit for immediate use after they have been removed from storage, requiring a considerable period of time for airing to permit the objectionable smell to disappear.

It is the object of the present invention to provide a simple and convenient storage receptacle in which the garments or other articles which require protection may be easily and quickly placed and from which they similarly may be easily and quickly removed, at all times being protected from the moths by a screen, as it were, of strong vapor of the moth balls or other material which guards any clearance space or crack through which they might gain access to the interior of the receptacle, sufficient vapor being also supplied directly to such interior to protect from any moths already in the receptacle or garments.

A further object of the invention is to provide the storage receptacle, preferably a drawer of a chest or the like, with a space or recess in the wall or front of the drawer, open at the top to receive the moth balls and to permit the escape of the vapor therealong, and having communicating passages from the recess to the interior of the drawer to permit the vapor also to pass directly into the interior of the drawer into contact with the garments stored therein.

To the above ends the present invention consists in the drawer or other receptacle embody-

ing the features of construction shown in the accompanying drawing and described in this specification and particularly defined in the claim appended hereto.

5 In the drawing, which illustrates a preferred form of the present invention, Fig. 1 is a top plan of the front of a drawer of a storage chest or the like and portions of the sides and bottom, constructed in accordance with the present invention, with certain portions broken away to show the parts beneath; Fig. 2 is a rear elevation of such drawer front with the sides and bottom of the drawer in section, showing the method of tilting the closures of the top of the recess to permit their easy removal, also with parts broken away; and Fig. 3 is a vertical section of the drawer front on the line 3—3 of Fig. 1, looking in the direction of the arrows.

In applying the present invention to the common type of chest drawer, a recess or pocket 5 is formed in the back face of the drawer front, conceivably by means of a plurality of saws or similar rotating tool, which removes the material from the back face approximately two-thirds of the distance to the front face and downwardly for perhaps half the distance from the top edge of the drawer to the bottom, leaving end walls 7 of large radii of curvature, and a flat bottom 9 for approximately half the length of the recess. Within the recess are spacer blocks 11 spaced from the end walls and from one another distances slightly greater than the diameter of a moth ball. These blocks are set below the level of the top of the drawer a distance equal to the thickness of the top closures 13 which normally rest upon the top faces of the blocks and are provided with a plurality of openings or passages 15. The spacer blocks, which are both formed with a groove 16 on their top faces, extend the lengths thereof beneath the passages 15 in the closures. They are preferably glued to the back of the recess and are provided with rounded ends, as shown, their outer ends 17 being rounded on the bottom to permit the free passage of moth balls to be inserted in the recess through the opening 21, and being rounded at their inner and upper ends, as at 23, so that by pressing down upon the inner end 25 of a closure piece the outer end of the latter may be raised as shown in Fig. 2, to permit it to be clasped by the hand and lifted out to allow moth balls 26 to be supplied to the end portions of the recess. The adjacent inner ends of the spacer blocks are separated to provide a sufficient width of passage 27 through

which moth balls may be supplied to the middle portion of the recess.

The inner face of the recess is closed by a panel 31 secured by screws 33 to the inner face of the drawer front and the filler pieces. Openings or passages 35 are formed in the panel to permit circulation of air between the recess and the interior of the drawer to carry the vapor of the moth balls or other protective material to the garments stored in the receptacle. These openings are shown in Fig. 2 in an ornamental design to add attractiveness to the construction.

The usual sides 37 and bottom 39 are provided for the drawer, as well as a back which is not shown in the drawing.

In use, the closures 13 are removed and the desired amount of moth balls inserted in the recess through the middle opening 27 and the end openings 21. Preferably the recess or pocket 5 is of a size to hold the entire contents of the standard box or package in which the moth balls are sold to the public, thus avoiding the objectionable odors which emanate from an opened, partially filled box of these balls standing on a medicine closet shelf or in some other open space. After filling the recess, the closures are replaced and the drawer is ready to receive the garments or other articles. These may be folded and stored in the drawer immediately or at some time in the future and from time to time without the necessity of hunting up a supply of moth balls to pack them in and around the garments whenever they are to be put in storage.

From time to time the amount of moth balls or other material in the recess may be checked by merely opening the drawer slightly and lifting one of the closures, and more moth balls may be added, as may be required, to maintain the proper density of vapor within the drawer.

By reason of the channels or grooves in the top spacers and the overlying passages in the closure, the vapor from the moth balls is supplied directly to the top of the drawer front, thus sealing the crack or clearance between the top of the drawer front and the adjacent cross-member of the chest with a strong vapor screen of protective material which will effectively prevent the entrance of any moths through such clearance space into the storage drawer. The vapor also passing through the openings in the

panel, supplies a sufficient amount to protect the garments, yet without saturating them to such an objectionable extent as when the moth balls are packed directly in and around the garments themselves.

The container for the moth balls being formed in the front of the drawer, it may be filled or inspected with only a minimum opening of the drawer being required, and when the garments 10 are placed in or removed from the drawer, there is no disturbance of the protective material, or requirement for an additional supply. Being formed in the drawer front, these recesses or 15 containers reduce the capacity of the drawer by only the thickness of the panel, and if desired, this inner wall could obviously be constructed in such manner that it did not project at all into the interior of the drawer.

While the invention has been described as embodied in a drawer of a storage chest, it is obvious 20 that it could be applied to other types of storage receptacles. Nor is it limited to use with naphthalene or moth balls, as other well known protective materials could be used both for moths 25 as well as for other destructive insects.

Having thus described the invention, what is claimed is:

A protective storage drawer having a wooden front with its back face cut away to form a recess extending along the back face of the front, with curved end walls and substantially straight bottom, a pair of spacer blocks secured in the recess adjacent the top of the drawer front, spaced from the ends of the recess and from one another 30 to provide filling openings, one of the ends of each block being downwardly curved, a perforated panel covering the recess and secured to the back face of the drawer front and to the spacer blocks, the top edge of the panel being 35 substantially flush with the top of the drawer front, and a pair of removable closures supported by the spacer blocks with their top surfaces substantially flush with the top of the drawer front, the closures normally closing with 40 a loose fit the top of the recess and one end of each closure overlying the curved end of a spacer block to facilitate the removal of the closure to permit protective material to be supplied through the filler opening to the interior 45 of the recess.
